UNITED STATES PATENT OFFICE.

LAWRENCE H. JENSEN, OF ST. CHARLES, ILLINOIS.

PUMP.

1,396,214.

Specification of Letters Patent.

Patented Nov. 8, 1921.

Application filed February 14, 1920. Serial No. 358,657.

To all whom it may concern:

Be it known that I, LAWRENCE H. JENSEN, a citizen of the United States, residing at St. Charles, in the county of Kane and State 5 of Illinois, have invented certain new and useful Improvements in Pumps, of which the following is a specification.

The invention relates to pumps of the hand operated type for inflating tires, tanks 10 and the like; and it has for its object the provision of a pump of a very practical character in that it may be operated with a maximum degree of efficiency and may be constructed at a very low cost.

15 More specifically, an important object of the invention is to provide an advantageous construction of operating mechanism in a pump of the character referred to, in which the effective power exerted upon the pump 20 piston by the pump handle rapidly increases with the increase in compression within the pump cylinder.

In the accompanying drawings I have 25 illustrated a preferred embodiment of my invention, but it will be understood that changes in construction without departing from the spirit and scope of the invention as defined in the appended claims are contemplated.

30 In Figure 1 of the drawings, I have shown a side elevation of my improved pump with a portion of the handle being broken away, the position of the parts when the piston has reached the end of its stroke being shown in broken lines. Fig. 2 is an edge elevation 35 of the pump with the operating handle broken away and shown in Fig. 2a. Fig. 3 is a sectional view taken on line 3—3 of Fig. 1 on an enlarged scale and showing a 40 detail of construction. Fig. 4 is a similar view taken on line 4—4 of Fig. 3.

The device comprises essentially a foot or 45 base plate 1, a pump cylinder 2 pivotally mounted upon the base plate and having a piston 3 with a rod 3a operatively mounted therein. 4 designates a support also pivotally mounted on the base plate 1 and providing a fulcrum for an operating arm 5 and a lever 6 connected at its opposite end to the 50 piston rod 3a. The operating arm 5 has a movable connection with the lever 6 which is designated generally by the numeral 7.

The base 1 and pump cylinder 2 with the piston 3 and rod 3a may be of any usual or 55 preferred construction, forming *per se* no part of the present invention, the cylinder 2

being provided with the usual outlet 8. The base plate has an upstanding portion 9 upon the upper end of which, on a pivot 11 is pivotally mounted a bracket 10 carrying the 60 pump cylinder 2.

The support 4 is pivotally mounted relative to the base plate 1 and preferably coaxially with the pump cylinder 2 upon the pivot pin 11. Preferably it comprises a pair 65 of bars 4^a and 4^b made of a length substantially greater than the pump cylinder and spaced apart as shown in Fig. 2. They thus form a rigid swinging bracket or frame, the bars being connected near their free ends by 70 pivot pins 12 and 13 and mounted at their lower ends at opposite sides of the bracket 10 upon the pivot pin 11.

The pivot pin 12 also serves as a pivotal support for the operating arm 5, being for 75 this purpose positioned a short distance from the free end of the support 4. Similarly the pivot pin 13 provides a pivotal support for the lever 6 at the free end of the support 4. The arm 5 may be bifurcated 80 in form as shown in Fig. 2, comprising a pair of arms 5^a and 5^b spaced apart sufficiently to fit neatly between the bars 4^a and 4^b at their pivotal connection therewith, and connected at their upper ends by means of a 85 pair of pins 15 and 16 with sufficient space between them to receive the lower end of an operating handle 17. The pin 15 may be made rigid with the handle so as to engage in notches 15^a in the upper ends of the arms 90 5^a and 5^b, and the lower end of the handle 17 may be notched as at 18 (dotted lines Fig. 1) to engage with the pin 16 which is in the form of a clamp screw provided with a wing nut to clamp the handle in position 95 with reference to the arm 5.

The lever 6 is in the form of a single bar, being spaced midway between the upper ends of the bars 4^a and 4^b upon the pivot pin 13 and suitably connected with the upper end of the piston rod 3a by means of a member 19 and pivot 20.

The sliding connection between the operating arm 5 and the lever 6 may be of any desired character, being preferably 105 constructed with a view to minimizing friction. Herein it consists of a U-shaped member or strap 21 pivotally mounted upon a pin 22 carried by the arms 5^a and 5^b of the operating arm 5 at a point a short distance above the fulcrum 12 of said arm. Upon said pin 22, and fitting neatly be-

between the free ends of the member 21, is mounted a roller 23 which is adapted to operatively engage with one edge of the lever 6, the strap member 21 being proportioned so that the space between the roller 23 and the yoke of the strap is adapted to neatly receive the lever 6. It will be seen that the strap serves to maintain the lever and the roller 22 in operative association during the return stroke of the operating arm and that in the operating stroke there is substantially no friction between the strap and the lever. In such operating stroke, as the parts are moved from the position shown in full lines in Fig. 1 to that shown in broken lines, the relative position of the parts varies in order to effect a rapid movement of the piston rod when the compression within the cylinder is comparatively slight, and a slower movement of the rod and greater force upon it as the compression within the pump cylinder builds up. And finally, when the parts are in the position shown in broken lines, the operating arm exerts a maximum degree of force upon the piston rod, the effective leverage being at this point, the greatest. In order to properly coördinate the rate of movement of the piston 3 with the position of the roller relative to the lever 6, the latter may be suitably shaped as at 6^a. As will be observed, the lever 6 and piston rod 3^a form in effect a toggle the parts of which are adapted to be moved into substantial alignment in the operation of the arm 5.

It has been found in practice that the pump which I have thus produced is capable of use in filling steel tanks with compressed air to a degree of pressure several hundred pounds greater than is possible with pumps as heretofore constructed. This is due to the fact that the peculiar arrangement of the parts which I have produced, causes the effective leverage exerted by the operating handle upon the piston rod as the degree of compression within the pump cylinder rises to rapidly increase, thus enabling the accomplishment of a greater amount of work with the expenditure of a minimum amount of effort by the operator. Moreover, the construction is very simple so that it may be cheaply manufactured and is of relatively great durability.

I claim as my invention:

55 1. In a pump comprising a cylinder having a piston therein and a rod for operating the piston, the combination of a pivotally mounted support, a lever connecting said support with said piston rod, and an arm pivotally connected with said support at a point between the pivotal connection of said lever therewith and the pivoted end of the support, and a sliding connection between said operating arm and said lever.

65 2. In a pump comprising a cylinder hav-

ing a piston rod, the combination of a pivotal support or fulcrum, a pivotal connection between the support and the rod including a lever, and an operating arm operatively associated with said support and having a slidable connection with said lever whereby the effective leverage exerted by the arm upon the piston rod increases as the compression in the cylinder rises.

3. In a pump comprising a cylinder and a piston rod, the combination of a pivotal support, a lever connecting the free ends of said rod and support, an arm pivotally connected with said support a short distance from its free end and having a sliding connection with said lever, and means for swinging said arm.

4. In a pump comprising a cylinder and a piston rod, the combination of a support upon which the cylinder is pivotally mounted, a second support pivotally mounted upon the first support and of a length substantially greater than the length of the cylinder, a lever connecting the free end of the second support with the free end of the piston rod, an arm pivotally connected with the second support at a point removed from the connection of the lever therewith, means for swinging the arm, and means slidably connecting said arm with said lever whereby the effective force transmitted by the lever from the arm to the piston rod increases gradually as the rod approaches the end of its stroke.

5. In a pump comprising a cylinder and a piston rod, the combination of a support upon which the cylinder is pivotally mounted, a second support pivotally mounted upon the first support and of a length substantially greater than the length of the cylinder, an operating arm, a lever connecting the free end of the second support with the free end of the piston, a connection between said arm and said lever comprising a U-shaped strap pivotally mounted upon the arm and slidably engaging with one edge of the lever, and a roller carried by the arm and operatively engaging with the other edge of the lever.

6. In a pump comprising a cylinder having a piston with a piston rod, the combination of a member of a length substantially equal to the combined length of the cylinder and piston rod, said cylinder and member being mounted for relative swinging movement, a member pivotally connecting the free end of the first mentioned member with said rod and forming with said rod in effect a toggle, and means fulcrumed on the first mentioned member and slidably connected with the second member for movement relative to the latter whereby to move the parts constituting the toggle substantially into alignment.

7. In a pump having a piston rod, the combination of a support, a lever pivoted to

- the support and also to the piston rod, and means including a second lever fulcrumed on the support and operable upon one edge of the first lever whereby to exert a gradually increasing leverage upon the piston rod as the latter approaches the end of its stroke, said connection including a roller on the second lever and said first lever having a curved surface with which said roller engages.
- 5 8. In a pump having a piston rod, the combination of a support, a lever pivoted to the support, and also to the piston rod, and an operating arm also pivoted to the support and carrying a roller adapted to operatively engage the lever, the surface on the lever with which the roller engages being curved to control the rate of movement of the piston with reference to that of the operating arm.
- 10 9. In a pump having a support and a
- 15 cylinder arranged to swing relatively to each other, in combination, a piston rod, a lever pivotally connected to said support and to said piston rod, and an operating arm pivoted on said support and slidably connected to said lever to apply force thereto progressively between said support and said piston rod and drive said piston rod.
- 20 10. In a pump having a support and a cylinder arranged to swing relatively to each other, in combination, a piston rod, a lever pivotally connected to said support and to said piston rod, a portion of one edge of said lever having a curved contour, and an operating arm pivoted on said support and having means for slidably engaging the said edge of said lever to operate said piston rod.
- 25
- 30
- 35
- In testimony whereof, I have hereunto set my hand.

LAWRENCE H. JENSEN.
